(57) **CLAIM**

The ornamental design for a storage box as shown and described.

DESCRIPTION

FIG. 1 is a first perspective view of a storage box showing my new design;

FIG. 2 is a second perspective view of FIG. 1;

FIG. 3 is a third perspective view of FIG. 1;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top view of FIG. 1;

FIG. 9 is a bottom view of FIG. 1;

FIG. 10 is a sectional view taken along line **10-10** of FIG. 4;

FIG. 11 is a sectional view taken along line **11-11** of FIG. 6; FIG. 12 is a front view of FIG. 1 in which the storage box is in a closed state; and,

FIG. 13 is a sectional view taken along line **13-13** of FIG. 12.

The dash broken line portions of the storage box in FIGS. 1-13 represent unclaimed portions of the claimed design and form no part thereof.

1 Claim, 13 Drawing Sheets
